UNITED STATES PATENT OFFICE.

GEORGE A. WHITE, OF BOSTON, MASSACHUSETTS.

DIE FOR CUTTING HEEL-LIFTS.

SPECIFICATION forming part of Letters Patent No. 243,185, dated June 21, 1881.

Application filed April 23, 1881. (No model.)

To all whom it may concern:

Be it known that I, GEORGE A. WHITE, a citizen of the United States, residing at Boston, in the county of Suffolk and State of Massachusetts, have invented certain new and useful Improvements in Dies for Making Heel-Lifts; and I do hereby declare that the same are fully described in the following specification and illustrated in the accompanying drawings.

This invention relates to improvements in making heel-lifts for boots and shoes; and it consists of an improved die for this purpose, which die is made long enough to contain two or more heel-lifts arranged side by side, and wide enough for a single heel-lift, for which purpose the die is made with a straight-base cutting-edge bounded by right-angle cutting-edges, the upper ends of which are united by a concavo-convex cutting-edge, or modification thereof, as will be further described.

Heretofore heel-lifts have been made by first stripping the hide in parallel strips, which have afterward been divided either in single heel-lifts cut out with a die for this purpose or divided by means of an angular knife in pairs of heel-lifts, one above the other; but such method is objectionable, owing to the inequalities of the thickness of the hide and its bagging or bellying shape, by which the strips cut therefrom are rendered very unequal in thickness and width, and consequently when the heel-lifts are cut from such strips they cannot be produced of standard dimensions without waste of leather. By the use of my improved dies, in which two or more heel-lift sections are arranged side by side, I obtain a long and straight cutting-edge on one side of the die, which serves as a guide to cut on a continuous straight line, and in this manner I am able to dispense with a preliminary stripping up of the hide in parallel strips or bands, and by cutting the heel-lifts from such parts only which are suitable for the purpose I am able to produce heel-lifts of standard dimensions and so as to leave the remainder of the hide uncut without any waste, so as to use it for other sole-leather parts for boots and shoes.

The invention is fully represented in the accompanying drawings, in which Figure 1 rep-

resents a plan view of my improved die. Figs. 2 and 3 represent modifications thereof; and Figs. 4, 5, and 6 represent dies of double the width shown respectively in Figs. 1, 2, and 3.

In Fig. 1, the improved die is represented as composed of four sides—viz., a base or straight-guide cutting-edge, *a*, of a length equal to the width of two or more heel-lifts, right-angle cutting-edges *b b* at the extreme ends of the cutting-edge *a*, and a concavo-convex cutting-edge, *c*, uniting the upper ends of the cutting-edges *b b*, as and for the purpose set forth.

The modification shown in Fig. 2 is that the concavo-convex cutting-edge *c* in Fig. 1 is substituted for a saw-tooth cutting-edge, *c'*, in said Fig. 2, and in Fig. 3 a continuous arched cutting-edge, *c''*, is substituted for the cutting-edges *c* and *c'* shown respectively in Figs. 1 and 2.

Figs. 4, 5, and 6 show dies of twice the width of those shown respectively in Figs. 1, 2, and 3. The dotted lines shown in the various figures of the drawings indicate division-lines on which the continuous heel-lift blanks are divided in pairs, located side by side preparatory to their being delivered or sold to the trade.

In using my improved die I dispense entirely with the operation of trimming or marking the hide to a straight edge, to serve as a guide for the workman in placing the die in a continuous straight line, as my dies have a straight-base guiding and cutting edge long enough to take in two or more heel-lifts side by side.

What I claim is—

The improved die for cutting heel-lifts, having a straight-guide cutting-edge, *a*, long enough for the width of two or more heel-lifts side by side, the right-angled cutting-edges *b b*, and concavo-convex cutting-edge *c* or its equivalent, in a manner and for the purpose set forth.

In testimony whereof I have affixed my signature in presence of two witnesses.

GEORGE A. WHITE.

Witnesses:

ALBAN ANDRÉN,
FRANCIS ALLEN.
